UNITED STATES PATENT OFFICE.

ISAAC H. LEITER, OF NEW YORK, N. Y.

DESIGN FOR GIMP.

SPECIFICATION forming part of Design No. 14,952, dated April 8, 1884.

Application filed January 25, 1884. Term of patent 3½ years.

To all whom it may concern:

Be it known that I, ISAAC H. LEITER, a citizen of the United States, residing in the city, county, and State of New York, have 5 invented and produced a new and original Design for Gimps, of which the following is a specification, reference being had to the accompanying photograph, forming part thereof.

My new design for gimp consists of three 10 longitudinal bands, having transverse bars arranged at equal distances across and over the same, the bar crossing the central band resting upon the inner ends of the bars crossing the side bands, which has the effect of placing 15 the central band slightly in advance of the side bands. The said bars may be so arranged over the bands as to present a raised appearance, thus giving to the design a peculiar and pleasing effect. All the bands may be made

of the same width; but I prefer to have the 20 side bands somewhat narrower than the central band.

The photograph represents a top view of my new design.

a represents the central band, *b* the side 25 bands, and *c c e* the transverse bars.

I claim—

The new design for gimp, which consists of the central band, *a*, and side bands, *b*, which bands are crossed at equal distances by transverse bars *c*, the bar crossing the central band resting upon the inner ends of the bars crossing the side bands, in the manner shown and described.

ISAAC H. LEITER.
